UNITED STATES PATENT OFFICE.

WALTER A. MEYER, OF BROOKLYN, NEW YORK, ASSIGNOR OF ONE-HALF TO RICHARD JAEGER.

POWDER PUFF AND PAD.

1,095,998.

Specification of Letters Patent.

Patented May 5, 1914.

Application filed September 12, 1913. Serial No. 789,409.

To all whom it may concern:

Be it known that I, WALTER A. MEYER, citizen of the United States of America, residing at Brooklyn, in the county of Kings and State of New York, have invented certain new and useful Improvements in Powder Puffs and Pads, of which the following is a specification.

The present invention relates to a combination lady's powder puff and pad, and consists in that the powder puff is made in form of a bag having a tube-like flexible extension through which the puff is filled and which can be folded into a pocket formed between the puff and the pad fixed to it.

To render my invention more clear, the same is illustrated in the accompanying drawing in which similar reference characters denote corresponding parts and in which—

Figure 1 is a front elevation of the device and Fig. 2 a longitudinal section on line 2—2 of Fig. 1.

The powder puff is made of cloth or other fibrous material in form of a bag *a*, preferably of an integral piece folded upon itself and stitched around its edges, leaving a narrow opening *a'* at the top to the edges of which a tube *b* made of cloth or other suitable material is stitched. This tube serves for filling the bag with the powder *c* to be

contained therein. Fixed to one side of the puff so as to form a pocket *e'* between itself and the puff is a pad *e* of soft, woolly material. Through the opening *e²* formed between the free edge of the pad and the puff the tube *b* may be folded into the pocket *e'*, after the puff is filled with powder.

In use the puff is "knocked" against the part to which the powder is to be applied, whereby the latter is pressed outwardly through the pores or holes *a³* between the fibers of the material. By the woolly pad some excess of powder may be easily removed and the powder layer rendered uniform.

What I claim and desire to secure by Letters Patent is:

A combination lady's powder puff and pad, consisting of a bag formed of porous and soft material and having a flexible member through which the powder is poured in, and a pad of soft and woolly material fixed to said bag and forming a pocket with the latter into which said member is folded, after the bag is filled.

In testimony whereof I affix my signature in presence of two witnesses.

WALTER A. MEYER.
